UNITED STATES PATENT OFFICE.

WILLIAM S. GRAFTON, OF WHEELING, WEST VIRGINIA, ASSIGNOR TO THE WHEELING CORRUGATING COMPANY, OF SAME PLACE.

DESIGN FOR A METALLIC MOLDING.

SPECIFICATION forming part of Design No. 23,050, dated February 6, 1894.

Application filed January 8, 1894. Serial No. 496,196. Term of patent 7 years.

To all whom it may concern:

Be it known that I, WILLIAM S. GRAFTON, a citizen of the United States, residing at Wheeling, in the county of Ohio and State of West Virginia, have invented and produced a new and original Design for a Metallic Molding, of which the following is a specification, reference being had to the accompanying drawing, forming part hereof, which shows a metallic molding designed according to my invention.

My design consists of a metallic molding having a horizontal, curved roll or bead A, below which is arranged a series of pyramidal projections B. The roll is subdivided into sections a, by transverse ribs a', arranged in transverse depressions a² in the roll A. These ribs a' divide the roll A, into sections a, approximately equal in width to the width of the pyramids B.

Above the roll A, is a beaded edge piece C,

provided with convex, circular projections D, arranged at equal distances apart on the edge piece, and having concave, central depressions d. There is a corresponding plain edge piece E, at the edge of or below the series of pyramids B.

The essential feature of my design is a metallic molding having a roll or bead arranged in line with a series of pyramidal projections, and divided by transverse ribs into sections corresponding in width to the width of the pyramidal projections.

I claim—

The design for metallic molding herein shown and described.

In testimony whereof I have hereunto subscribed my name.

WILLIAM S. GRAFTON.
